[57] CLAIM

The ornamental design for an electrical box holder,
substantially as shown and described.

DESCRIPTION

FIG. 1 is a perspective view of an electrical box holder
showing my new design.

FIG. 2 is a side elevational view of the electrical box
holder, drawn to an enlarged scale, the opposite side
elevational view being a mirror image thereof.

FIG. 3 is a top plan view thereof.

FIG. 4 is an elevational view of the electrical box
holder, as seen from the left of its FIG. 2 position.

FIG. 5 is an elevational view thereof, as seen from the
right of its FIG. 2 position.

FIG. 6 is a bottom plan view thereof.
